PAGE 2

Fig. 2.

Fig. 5.

Fig. 3.

Fig. 1 is a front elevational view of a magnetic tape recorder, showing my new design;

Fig. 2 is a rear elevational view thereof;

Fig. 3 is a front elevational view thereof with the cover removed;

Fig. 4 is a top perspective view with the cover removed; and

Fig. 5 is a side perspective view of the magnetic tape recorder with the cover removed.

The opposite side of the magnetic tape recorder is plain and without ornamentation.

I claim:

The ornamental design for a magnetic tape recorder, as shown and described.
